MAGNETIC PEELER FOR PROTON
SYNCHROTRON

Milton Stanley Livingston, Belmont, Mass., assignor to the United States of America as represented by the United States Atomic Energy Commission

Application February 21, 1950, Serial No. 145,401

5 Claims. (Cl. 313—62)

1

The present invention relates to a method and apparatus for deflecting accelerated high energy charged particles from curved orbits in a particle accelerator such as a synchrotron, a betatron or others which confine the path of the accelerating particles to a generally circular one.

Ion accelerators, of the type which confine particle motion to a generally circular path, employ a magnetic field which increases in strength as the ion velocity increases to maintain motion in a circular path of approximately constant radius. When the accelerated ions have attained a desired energy or velocity some means must be provided to cause the ions to be deflected from their confined paths in a controlled manner and to be thus removed from the accelerator.

It is accordingly an object of the present invention to provide a novel method and apparatus for deflecting ions from a generally circular orbit in a particle accelerator.

It is another object of the present invention to provide a method and apparatus for deflecting ions from a generally circular orbit which apparatus is operated automatically responsive to the generation of energy in said accelerator.

Other objects and advantages will be in part obvious and in part pointed out hereinafter.

In one of its broader aspects the method of the present invention comprises changing the magnetic properties of the path-restricting magnet in a region along a relatively short segment adjacent the path to which the ions are confined during their acceleration and changing the radius of curvature of said particles in the apparatus to bring them into the region of changed magnetic properties. An apparatus which has been found particularly suitable for carrying out the method of the present invention comprises means for changing the magnetic flux of a short segment adjacent the closed curvilinear path about which said particles are being accelerated and means for moving said flux changing means toward and away from the ion path.

The present invention will be described with reference to a proton synchrotron although it will be understood that the method and apparatus such as is described in this embodiment is applicable with slight modification to the removal of accelerated ions from other particle accelerators employing a magnetic field which increases with time to restrict the ion motion to a closed curvilinear path.

It is believed that clarity of the explanation of the present invention will be aided by reference to the drawings wherein:

Figure 1 represents a top plan view of a synchrotron in conjunction with which the present application may be employed.

2

Figure 2 represents a sectional view of the synchrotron taken along angulated line 2—2 of Figure 1.

Figure 3 represents a vertical section taken along the line 3—3 of Fig. 4 of one embodiment of the apparatus of the present invention shown in position with respect to a channel in which acceleration of particles is carried out.

Figure 4 is a front elevational view of Figure 3 taken along a line 4—4 of Figure 3.

Figure 5 is a detailed view of a magnetic deflector channel which has been found satisfactory for use according to the present method.

Figure 6 is a top plan view in part in section of the apparatus of Figures 3 and 4.

Referring to Figures 1 and 2 a pulse of protons is injected into an evacuated generally ring-shaped chamber 98 by means of an electrostatic generator 100 of the Van der Graaf type. Vacuum is maintained in the chamber by continuously withdrawing gas through the conduits 82 which connect the chamber 98 to the pumps 80. In traveling between the electrostatic generator 100 and the chamber 98 the charged particles pass through conduit 102. On their arrival in the evacuated chamber 98 particles are deflected into the generally ring-shaped path, defined within the chamber 98, by a suitable charge on the electrostatic deflector plates 104 located at the opening where the conduit 102 joins the chamber 98. The charge is supplied to the deflector plates 104 through the electrical connections 105 from a suitable power source 107. As the particles travel along the path within the chamber 98 they pass through and are caused to curve along a generally ring-shaped region or core 99 centrally located in the chamber by the action of a magnetic field permeating the curved portions of the chamber. The magnetic field is set up to permeate the curved portions of the chamber between the jaws of four magnet quadrants 106, 110, 114 and 118, these magnet quadrants having a generally C-shaped cross section (best seen in Figure 3).

The power used in generating the magnetic field in the magnet quadrants is supplied from the dynamo motor assembly 92 through the conductor 91 which passes through the innermost portions of the jaw openings in the C-shaped quadrants 106, 110, 114 and 118. The dynamo motor assembly 92 consists of a pair of rotatable electric machines or dynamos 90 which may be operated as either generators or motors and are mechanically coupled to a pair of fly-wheels 88, the dynamos being electrically connectable through the switch 89 to the conductors 91 or a source of electric power (not shown) through the conductors 87. The energy to be used in building up the magnetic flux in the jaws of the magnet quadrants is

delivered from the dynamos 90 to the quadrants through the conductors 91. A very large amount of electrical energy must be delivered within a relatively short time in order to build up the desired flux density across the jaws of the magnet quadrants. By connecting the dynamos 90 through the switch 89 to a source of electric power through the conductors 87 the dynamos are made to act as motors and store the necessary energy in the rotating fly-wheels 88. When the fly-wheels have reached a desired velocity the switch 89 is thrown thereby connecting the dynamos 90 to the conductors 91. The energy stored in the fly-wheels is converted to electrical energy by the rotation of the dynamos, which in this connection act as generators to generate the electricity necessary to energize the magnet quadrants 106, 110, 114 and 118. As the particles pass between the quadrants they describe a relatively straight path and therefore, those portions 108, 112, 116 and 120 of the wall of the chamber 98 are straight.

The acceleration of the ions is achieved by imparting an accelerating energy thereto as they pass through the ring member 124 enveloping a short section of the straight portion 116 of the chamber 98. The energy is applied at predetermined intervals from the pulse generator 140, the frequency mixer 142, and the voltage generator 200 as described in the copending application of John P. Blewett, S. N. 60,991 filed November 19, 1948. The voltage generator 200 is activated by the trigger detector mechanism 148 also described in the Blewett application. By maintaining a balance between the acceleration of the particles and the increasing magnetic field permeating the curved portions of the chamber 98, particles are caused to continuously rotate within the chamber 98 in relatively stable orbits.

As the ions are accelerated in phase with the increasing magnetic field between the jaws 94 and 96 of the magnet quadrants, they tend to be confined to stable orbit paths which are centrally located in the annular core 99 of the chamber 98. During the initial portion of the acceleration period the ion paths are not confined to the core 99 but fill a substantial volume of the chamber 98 due to both vertical and radial oscillation from the core 99. During this portion of the acceleration period, when the ion paths are not confined to the center of the chamber 98, it is necessary to keep the portions of the chamber through which the ion paths deviate free from any article which would be struck by the ions or which would cause the ions to be deflected from their paths of travel within the chamber.

By the method of the present invention ions are deflected from an evacuated ring chamber after having been accelerated to a desired velocity by changing the phase relation of the accelerator so as to cause the ions traveling in the central portion of the chamber to be deflected toward the radially outermost portions thereof and by providing a region of reduced magnetic flux density along a segment of the outermost portions of the chamber.

Referring to Figures 3, 4 and 6, an apparatus suitable for carrying out the objects of the present invention is shown in place in a modified form of the apparatus of Figures 1 and 2 and consists essentially of the following. The magnetic field which is generated in the "C" magnet having pole faces 194 and 196 is augmented in this modified illustration of the example by the electrical windings 20 (seen best in Figure 3) located at the outer extremity of the pole faces. These

windings 20 are held in place by the brackets 22. The ions are deflected from their orbits in the evacuated chamber 198 (having in this modification a rectangular cross section) by means of a peeler unit 10. For the proton synchrotron, a preferred location of the peeler unit is the section of a magnetic quadrant preceding a straight section of the chamber 198 with reference to the direction of travel of the ions. However it may be located at any desired point within the magnetic field of the magnet quadrants. The peeler comprises an axially movable rod member 28 which is hermetically sealed through the chamber wall, threaded along its externally extending portion, and supporting at its internal end a channel bar 204. The bar 204 is provided with a channel 202 which is aligned with the path of flight of the ions. The rod 28 is slidably supported in a bearing tube 26 and prevented from turning by the action of a key 44 extending from the rod 28 into a key way 45 in the internal bearing tube wall. The rod is urged to its greatest external extension by a spring 38 concentric to the rod, and compressed between the outer end of the bearing rod 26 and a nut 36 threaded on to the rod. The compression on spring 38 may be adjusted by axial movement of the nut 36 along the rod 26. The spring rests against shoulders 40 and 42 provided on the bearing tube 26 and nut 36 respectively. A hermetic seal is provided at the portion of the chamber wall through which the rod 28 passes in the form of a packing material 32 compressed between the internally threaded flange cup 34 and the nut 35 threaded therein. The flange 37 of cup 34 is sealed to the flange 39 of the recessed portion 12 of chamber 198. All of the metallic parts of the peeler 10 are preferably composed of non-magnetic material except for the channel bar 204.

With reference to Figures 3, 4 and 6 the operation of the peeler may be described as follows. When the protons are initially introduced into the chamber 198 from a Van de Graaf accelerator they tend to oscillate vertically and radially about the core 199 of the chamber 198. During the initial acceleration period while the oscillations are at a maximum, the channel bar 204 (shown in phantom as 204¹) is held in the recessed portion 12 of the chamber 198 by the action of spring 38. As the oscillations of the ions are damped, the ion paths become confined to the core 199 of the chamber 198 and the magnetic field between the pole faces 194 and 196 increases. Increase in the magnetic field strength is necessary in order to maintain ion motion in a circular path of approximately constant radius and confine them to the chamber 198. According to a preferred embodiment, the compression on the spring 38 is adjusted by movement of the nut 36 along the rod 28 to allow the magnetic pull of the "C" magnet on the channel bar 204 to overcome the spring pressure on the rod 28 after the ions have been confined to the core 199 of the chamber 198, but before the ions have been accelerated to their desired energies. The channel bar 204 is thus brought into the chamber 198 after the ion oscillations have been damped. Its presence does not interfere with the initial acceleration of the ions in the chamber because while the ion paths fill a substantial portion of the chamber the channel bar is recessed in the projecting portion 12 of the chamber 198. The channel bar 204 is present, however, when the ions have been accelerated to a desired velocity and thus is available for their removal.

Referring again to Figure 1 accelerated ions may be removed from chamber 98 along the path indicated by the arrows by introducing a channel bar 204 similar to that illustrated in Figure 5 into the chamber as part of a peeler unit 10'. As pointed out below the means for urging the channel bar 204 into the chamber may be any conventional means of effecting a precisely timed rapid movement of a member. Such means is represented by the unit 9 to which the peeler unit 10' is operatively connected. Once the channel bar is in place in the chamber the frequency of application of the accelerating voltage to the induction accelerator 124 is increased without increasing the magnetic flux between the pole faces sufficiently to restrict the ion paths to the core 99 and thereby cause the ions to be confined to the core 99. Rather the ions expand their orbits in the chamber 98 and are thus brought within the influence of the reduced magnetic field in the channel of bar 204. The effect of ions passing through the region of reduced magnetic field within the channel 202 of bar 204 is to change their path of flight from a generally circularly curved path due to the influence of the magnetic field between the pole faces 94 and 96, to a relatively straight or tangential path. As a result, when the ions reach the straight portion 108 of the channel 98, their direction of travel carries them through the port 109 from the channel 98 or to any apparatus aligned with this port along the path of ion flight. The length of the bar 204 is determined by the angle of deflection desired, the field reduction obtainable in the groove, and the curvature of the orbit. For a 50% reduction in the field strength between the magnetic poles to occur within the channel 202, the length of the channel bar should be such as to subtend an arc of the orbit having an angular value equal to twice that of the deflection desired.

In operation, the magnetic peeler described therefore provides an effective means for removing ions which have been accelerated to desired energies from the proton synchrotron or similar apparatus at a desired point of the apparatus and with a high degree of control. In the operation of the proton synchrotron described in the Blewett application referred to above, assuming the period of acceleration to be approximately one second and the lateral oscillations of the ions causing them to fill the entire horizontal extent of the tube to last for approximately one-tenth of a second, approximately nine-tenths of a second remains for the channel bar 204 to be brought into position in the chamber 98 to effect the removal of the ions. Alternative methods are contemplated according to the present invention for introducing the channel bar 204 into position during this period. For example, an electronic solenoid powered by external circuits which are pulsed at appropriate times may be used. Similarly a hydraulic ram in which a piston is driven by fluid or gas pressure operated by valves, or a mechanical system driven by cams or levers may be substituted for the above-described scheme for utilizing the varying magnetic field of the magnet quadrants of the synchrotron for automatically moving the peeler channel rod into place. Conventional means for activating the valves or levers in time with the changing magnetic field in the quadrants may be employed. One such activating apparatus, a peaking strip, is described in the copending application of J. P. Blewett referred to above.

Since many embodiments might be made of the

present invention and since many changes might be made in the embodiment described, it is to be understood that the foregoing description is to be interpreted as illustrative only and not in a limiting sense.

I claim:

1. An apparatus for changing the trajectory of high energy ions moving in a curvilinear path in a magnetic field in order to eject said ions from said field in a controlled member which comprises an elongated magnetic metal member having a longitudinal channel therein, means for moving said channel in said magnetic field toward and away from said curvilinear path and for keeping said channel aligned with said path.
2. An apparatus for changing the trajectory of high energy ions moving in a curvilinear path in a magnetic field in order to eject said ions from said field in a controlled manner which comprises an elongated ferromagnetic member having a longitudinal channel therein, means for moving said channel in said magnetic field toward and away from said ion paths and for keeping said channel aligned with said paths.
3. In a synchrotron for accelerating ions to very high energies a channel bar member the channel of which is aligned with and confronts the path of travel of ions in said synchrotron, said bar being movable in said magnetic field toward and away from said ion paths responsive to the change in magnetic flux through which said ions move whereby the trajectory of said ions in said magnetic field may be changed as said ions pass through the channel of said member.
4. In a synchrotron for accelerating ions to very high energies including an evacuated ring chamber in which said ions are confined by a magnetic field permeating said chamber, an apparatus for removing said ions from said chamber which comprises a rod hermetically sealed through the chamber wall in sliding relation, a channel bar affixed to the internal end of said rod, the channel of said bar being aligned with and confronting the path of travel of ions in said chamber and external means for moving said rod toward and away from the path of flight of said ions in said chamber.
5. In a synchrotron for accelerating ions to very high energies including an evacuated ring chamber in which said ions are confined by a magnetic field permeating said chamber, an apparatus for removing said ions from said chamber which comprises a rod hermetically sealed through the chamber wall in sliding relation, said rod supporting at its internal end a channel bar, the channel of which is aligned with and confronts the path of travel of said ions in said chamber and spring means operatively associated with the externally projecting portion of said rod for urging said rod to its greatest external extension.

M. STANLEY LIVINGSTON.
